UNITED STATES PATENT OFFICE.

GEORGE H. LYON AND GABRIEL H. KARICOFE, OF DELRAY, MICHIGAN.

AIR-HEATER FOR STEAM-GENERATORS.

SPECIFICATION forming part of Letters Patent No. 747,198, dated December 15, 1908.

Application filed June 5, 1901. Serial No. 63,234. (No model.)

To all whom it may concern:

- Be it known that we, GEORGE H. LYON and GABRIEL H. KARICOFE, citizens of the United States, residing at Delray, in the county of Wayne and State of Michigan, have invented certain new and useful Improvements in Air-Heaters for Steam-Generators, of which the following is a specification, reference being had therein to the accompanying drawings.
- 10 The invention relates to attachments to steam-generators, and has for its object the improving of the combustion in the furnace, thereby economizing in fuel and reducing the smoke.
- 15 The invention consists in the peculiar construction of an air-heater which is adapted to utilize the heat otherwise wasted for heating a quantity of air which is subsequently introduced into the furnace-chamber.
- 20 The invention further consists in the peculiar construction, arrangement, and combination of parts, as hereinafter described and claimed.

In the drawings, in which the invention is shown applied to a locomotive, Figure 1 is a longitudinal section, partly in elevation, through a locomotive boiler and furnace to which the improvements are applied. Fig. 2 is a section on line xx through the fire-box 25 of the locomotive. Fig. 3 is a cross-section on line yy , Fig. 1.

A is a locomotive-boiler of any suitable construction provided at its forward end with the usual smoke-box B, to which is secured the stack C. Within the smoke-box is an exhaust-nozzle D and the usual deflector-plate E, which extends from a point just above the flues downward and forward, as shown. This deflector-plate E is subject to direct heat of the flame and gases passing through the flues 30 into the smoke-box and is therefore heated to a high temperature, which heat is ordinarily wasted. With the present invention the heat of this plate is utilized by arranging directly forward thereof an air-heating drum F, which extends completely across the smoke-box in rear of the exhaust-nozzle D, the rear wall of said drum forming the deflector-plate. Forward of the stack C within the smoke-box 40 is arranged another heating-drum G, which extends across the smoke-box just above the door H. The drums G and F are connected

to each other, preferably by arranging a segmental casing I within the shell of the smoke-box, leaving the space between said shell and 55 said segmental casing, which forms an air-conduit connecting the chambers G and F.

J is a jacket arranged around the stack C, which is open at its upper end and at its lower end communicates through apertures α with 60 a drum G. Above this jacket is a conical deflector K, secured to the stack, which prevents the ingress of smoke.

L represents conduits connecting with the chamber F on opposite sides of the boiler and 65 extending longitudinally of the latter, preferably just within the outer jacket (not shown) to a point near the rear end of the boiler. Here they turn downward and are connected with casings M upon opposite sides of the fire-box. Connecting with these casings M are the flues N, extending through the water-jacket surrounding the furnace-chamber and establishing communication between said casings M and said furnace-chamber. At the 70 front of the fire-box is preferably arranged a casing O, which is open at its upper end and at its lower end connects with the ash-box. If desired, the casing P may also be used, covering the rear head of the boiler and 75 having an air connection with the ash-box M'.

The parts being constructed as shown and described, in operation the heat of the flame and gases passing through the flues into the smoke-box is first imparted to the deflector-plate E and is communicated therefrom to the air within the drum F. In passing around said deflector-plate the flame and gases also impart heat to the segmental plate I and to the drum G, and finally in passing out through 85 the stack heat is imparted to the air within the jacket J. As the conduit L connects the drum F with the casings M and as the latter are connected through the flues N with the furnace-chamber, it is evident that the 90 draft of the furnace will cause the air to be drawn in from said chambers M, and thereby will produce a current of air flowing inward, first entering the upper end of the jacket J, then passing into the drum G and through 95 the segmental passage-way into the drum F, and finally passing through the conduit L into the casings M. The result will be that the heat which would otherwise be lost is im-

parted to the air in passing through this conduit, and by the time it reaches the furnace-chamber the air is heated to a high temperature. Thus when introduced into the chamber **5** it will materially assist in the combustion of the fuel therein, both increasing the steam and preventing the formation of smoke. The combustion is assisted by the heated air which passes through the jacket O into the ash-pan **10** and by the heated air in the casing P, which is also turned into the ash-pan M' and introduced into the furnace.

If the quantity of air heated is greater than needed for assisting combustion, a portion **15** thereof may be drawn off and used for heating the cars or for any other purpose where heat is required.

What we claim as our invention is—

1. In a steam-generator, the combination **20** with a smoke-box and an inclined deflector-plate therein extending across opposite the ends of the flues in the path of the smoke and heated products and adapted to direct the same downward, of an air-drum arranged adjacent to said deflector-plate, a connection between said drum and the external atmosphere and a draft connection between said drum and furnace-chamber.

2. In a locomotive, the combination with a **25** smoke-box and a deflector-plate therein, of an air-heating drum arranged adjacent to said deflector in rear of the exhaust-nozzle

and stack, a second drum arranged forward of the stack, a connection between said drums, an air-inlet connection with the forward drum **35** and a connection between the rear drum and the furnace-chamber.

3. In a locomotive, the combination with a smoke-box and a deflector-plate therein, of an air-heating drum arranged adjacent to said **40** deflector-plate in rear of the exhaust-nozzle and stack, a second drum arranged forward of the stack and above the door of the smoke-box, a segmental plate within the shell of the smoke-box forming a connecting passage between said drums, a jacket surrounding the stack open at its upper end and connected with the forward drum and a conduit connecting the rear drum with the furnace-chamber.

4. In a steam-generator, the combination **45** with a smoke-box, of a deflector-plate therein, of an air-heating drum arranged adjacent to said deflector-plate, an air-inlet conduit adjacent to the stack and heated therefrom connected with said air-drum and a connection between said drum and the furnace.

In testimony whereof we affix our signatures in presence of two witnesses.

GEORGE H. LYON.
GABRIEL H. KARICOFE.
